UNITED STATES PATENT OFFICE

2,499,556

GAS-BURNING APPARATUS

John S. Zink, Tulsa, Okla.

Application October 25, 1946, Serial No. 705,541

4 Claims. (Cl. 158—7)

1

This invention relates to gas burning apparatus for furnaces and the like, and more particularly to a conversion burner to be employed in coal burning furnaces in substitution for the coal burning equipment.

One of the objects of the invention is to control the flow of gas and air in a particular way because if the stream of air flowing past the burner head is moving at high velocity and thereby sets up a condition of great turbulence, a number of undesirable phenomena is to be observed. One in particular is that of preventing the spread of the flame from the burner head to thus hinder efficient transfer of heat while another is the creation of undue combustion noise which is undesirable.

It will therefore be understood that another object of the invention is to supply a substantially noiseless gas burning apparatus.

A further object is to supply a unitary gas burning apparatus designed to make furnaces of limited heating area into an efficient heating unit comparable to specially designed gas-fired units.

With the foregoing objects outlined and with other objects in view which will appear as the description proceeds, the invention consists in the novel features hereinafter described in detail, illustrated in the accompanying drawings, and more particularly pointed out in the appended claims.

In the drawings:

Fig. 1 is a diagrammatical vertical sectional view of a furnace with my conversion burner installed therein.

Fig. 2 is an enlarged outer end view of the gas burning equipment.

Fig. 3 is a longitudinal vertical sectional view taken on the line 3—3 of Fig. 2.

Fig. 4 is a top plan view of the inner end portion thereof.

Referring to the drawings, 5 designates a conventional hot air furnace having an internal casting 6 forming a fire box or combustion chamber 7. Ordinarily such furnaces have a grate at the level 8 which separates the combustion chamber from the ash pit 9.

In accordance with the present invention, the grate is removed and my burner equipment 10 is inserted through the ash pit doorway 11, after which the space between the duct 12 and the doorway is closed by bricks 13, or the like.

As best shown in Figs. 2 and 3, the duct 12, which may be of sheet metal, is in the form of an elongated box of rectangular cross section provided at its outer end with a face plate 14 having a doorway 15 for the entrance of air. Introduction of the air may be controlled in any suitable way. For example, a door 15a may be hingedly connected at 16 to the face plate and be provided with ears 17 and 18 having threaded apertures to receive screws 19 and 20 which impinge upon portions of the face plate. It is ob-

2

vious that turning of the screws will result in opening or closing the door and holding it in any desired position of adjustment.

The face plate is provided with an outwardly projecting boss 21 through which a gas supply pipe 22 extends into the duct 12. The inner end of said pipe terminates adjacent the inner end 23 of the duct and is provided with an elbow 24 resting on a chair or bracket 25, secured to the bottom of the duct. The bracket has a notched horizontal arm 26 at its upper end for the reception of a short vertical pipe 27, having threaded connection with the elbow. A burner head 28 of special construction has a threaded boss 29 at its lower end, in threaded connection with the upper end of the vertical pipe.

At this point, it will be noted that the top of the duct is provided with a relatively large circular opening 30 into which the burner head extends, and as the burner head is arranged centrally of such opening, an annular air space 31 is provided between the burner head and the portion of the duct defining the opening 30. The duct has smaller air discharge openings or ports 32 arranged at opposite sides thereof, and an additional air discharge port 33 at the inner end thereof. Due to this construction, air introduced into the duct can be discharged into the furnace through all of said ports, some of the air travelling upwardly with the gas from the burner head and other air being diffused through the ports 32 and 33.

Referring to Figs. 3 and 4, it will be noted that the burner head has a frusto-conical top 34 arranged above the gas chamber 35 which communicates with the depending hollow boss of the head, and within such boss there is arranged a threaded plug 37 having an orifice 36 through which gas passes into the burner head. As the plug is threaded and removable from the burner head, it is obvious that plugs having different size orifices may be substituted one for another to regulate the amount of gas introduced into the burner head.

The conical wall 38 of the top of the burner head is provided with gas discharge ports 39 which preferably radiate from the axis of the burner head and extend upwardly and outwardly from the internal chamber of such head.

In accordance with the invention, the burner head is provided with an upwardly and outwardly extending rim or annular shield 40 to prevent air from the duct from immediately contacting the gas as the gas issues from the gas discharge ports.

In operation, gas is supplied through the pipe entering the air duct at or near the end upon which the air control means is provided, and such gas discharges through the ports of the head upon which the rim is preferably cast. Due to the construction and arrangement of parts, air for combustion in greater or lesser quantities

may be caused to flow past the head. The flow of air for combustion is, partially past the rim of the head, and the function of the rim is to prevent contact of the air with the jets of gas emerging from the gas ports immediately upon emerging from the head. The intent of this arrangement is to stabilize combustion of the gas and prevent what is called "blowing-off" of the streams of gas or failure of the gas to ignite immediately upon emerging from the head.

If the stream of air flowing past the head is moved at high velocity, it will set up a condition of great turbulence to prevent the spread of flame from the burner and thus hinder efficient transfer of heat while creating undue combustion noise. To counteract such tendency, I have provided the air discharge ports 32 and 33 at the opposite sides and inner end of the duct 12. The streams of air which flow through these ports enter the streams of fuel gently and by diffusion, at points removed from the head. Obviously, such air does not flow directly past the head as would be the case with a single opening 30.

Through the provision of a plurality of openings or ports 32 and 33, the velocity of air flow past the head is reduced to such a point that noise of combustion falls to a suitable level, and the flame spreads to assure efficient transfer of heat produced through the burning of the gas.

It is manifest that the radial width of the rim or shield 40 may be varied to obtain either completely diffused combustion or turbulent combustion in any degree required. Diffused combustion provides a highly luminous flame which is productive of a rich radiant heat transfer condition; however, a completely luminous flame requires more space for burning than is the case with increased turbulence and partially or completely blue flame.

As it is at times necessary to balance the space for burning the gas against the value of a luminous flame, I have thus provided means of controlling the type of combustion obtained, so as to retain as much luminosity in the flame as possible. Authorities agree, and it is well known to those versed in the art that a luminous flame is from two to seven times more efficient as a radiator of heat than is a clear or blue flame.

Any suitable means may be employed to ignite the gas from the burner head. For example, the burner head may be notched at one side, as indicated at 41, and the notched portion may be provided with a depending lug 42 to permit the attachment of a pilot burner head to the gas burner head, by means of a screw 43 or the like. The pilot burner will be supplied with gas through a tube 44 that extends through the face plate of the air duct.

While I have disclosed what I now consider to be a preferred embodiment of the invention in such manner that the same may be readily understood by those skilled in the art, I am aware that changes may be made in the details disclosed without departing from the spirit of the invention, as expressed in the following claims.

What I claim and desire to secure by Letters Patent is:

1. Gas burning apparatus comprising, a duct having an inner end, means at the other end of the duct for controlling the admission of air into the duct, said duct having an opening in the top portion adjacent the inner end, a burner head within said opening, said burner head having side ports, an annular rim extending upwardly and outwardly from below the ports in the burner head with an outer edge of the rim being spaced

inwardly from the edge of said opening to provide an annular space for air rising through said opening around said rim, means for supplying gas to the burner head, and said duct having an opening therein adjacent the inner end for the escape of part of the air from the duct.

2. Gas burning apparatus comprising, a horizontally disposed duct having an opening at one end, means at the other end of the duct for controlling the admission of air into the duct, said duct having a circular opening in the top portion adjacent the first end, a burner head mounted within said second opening, said burner head having a plurality of radially directed side ports circumferentially spaced therearound, an annular rim carried by the burner head extending upwardly and outwardly from below the discharge end of the ports with an outer edge of said rim being spaced inwardly from the boundary of the second opening to provide an annular space for air rising from the duct around said rim, and means for supplying gas to the burner head.

3. Gas burning apparatus comprising, a horizontally disposed duct having an opening at one end, means at the other end of the duct for controlling the admission of air into the duct, said duct having a circular opening in the top portion adjacent the first end, a burner head mounted within said second opening, said burner head having a plurality of radially directed side ports circumferentially spaced therearound, an annular rim carried by the burner head extending upwardly and outwardly from below the discharge end of the ports with an outer edge of said rim being spaced inwardly from the boundary of the second opening to provide an annular space for air rising from the duct around said rim, and means for supplying gas to the burner head.

4. In gas burning apparatus, a duct having an end portion adapted to be inserted in a furnace, means at the other end of the duct for controlling the admission of air into the duct and said duct having an opening in the top portion adjacent the inner end, a burner head within said opening, said burner head having a plurality of circumferentially spaced side ports, an inverted frustro-conical rim extending upwardly and outwardly from below the ports in the burner head with the upper and outer edge of said rim spaced inwardly from the boundary of said opening to provide an annular space for air rising from the duct through said opening around the rim, means for supplying gas into the burner head, and said duct having a plurality of openings therein for discharging air laterally of the burner head.
